TOOL FOR HANDLING OPEN-ENDED
RETAINING RINGS

Louis W. Schaaff, Jackson Heights, Sigmund Waldes, Flushing, and Rudolf Feitl, Brooklyn, N. Y., assignors to Waldes Koh-I-Noor, Inc., Long Island City, N. Y., a corporation of New York

Application November 17, 1944, Serial No. 563,888

3 Claims. (Cl. 29—229)

1

This invention relates to improvements in tools for handling open-ended retaining rings.

As is well known, difficulties are encountered in the handling for assembly and disassembly of open-ended retaining rings of the type adapted to be sprung into the groove of a shaft or a housing, for example, due to the fact that such rings must be spread or compressed in slipping them over the shaft or inserting them into the housing bore containing the grooves in which they seat. To assist in handling such rings, it has been proposed, for example in Reissue Patent No. 18,144, to form the rings at their open ends with apertured ears or lugs into which working points provided on plier-type handling tools are inserted for the purpose of spreading or compressing the rings, depending on whether the ring is of the external or internal type.

The forces which are required to be exerted on the handles of plier-type handling tools to spread or compress the rings as aforesaid the necessary amount to slip them over a shaft or to compress them for insertion into a housing bore are remarkably high for the larger size rings, and in the case of ring sizes of 6" or more can amount to approximately 150 lbs. Heretofore this heavy spreading or compressing force for the larger size rings was obtained by increasing the length of the plier handles thus to obtain additional leverage, but this leads to a cumbersome, heavy pliers construction and makes for difficulty in their operation and handling.

Moreover, in cases requiring the assembly or disassembly of a shaft located in a housing, or the assembly or disassembly of a ring in a housing groove surrounding a shaft, it is often not possible or feasible to use pliers with elongated handles because the available space between shaft and housing is usually quite restricted.

The present invention has for a principal object the provision of a hand-operated, plier-type tool for handling open-ended retaining rings as aforesaid which overcomes the disadvantages of the plier type tools as noted above. More specifically, the invention aims to provide a simple and thoroughly dependable tool of rod-like construction which employs working points protruding from an end thereof, together with means for effecting relative angular displacement of the points as required to spread or compress the ring. A further object of the invention is to provide a tool for handling open-ended retaining rings whose construction lends itself to the insertion of the tool into housing bore openings of restricted size. It is a further object of the inven-

2

tion to provide a rod-like tool of the stated character incorporating power-developing or amplifying means for effecting angular displacement of the working points, whereby the tool is adapted for the handling of larger size rings requiring a high degree of spreading or compressing force. A still further object of the invention is the provision of a rod-like tool for handling open-ended retaining rings which is characterized by interchangeability of its working head, so that the tool can be used for handling rings of different sizes. A still further object of the invention resides in the provision of self-locking driving or actuating means for the working points protruding from the head end of a rod-like tool as aforesaid, for example, a locking means as provided by a high-ratio, irreversible worm gearing having low friction.

Other objects will be in part obvious and in part hereinafter pointed out in connection with the following analysis of the invention wherein are illustrated embodiments of the invention in detail.

In the drawings:

25 Fig. 1 is a part-sectioned side elevation of one embodiment of a tool according to the invention; Fig. 2 is an end view of the rear or driving end of the tool illustrated in Fig. 1;

30 Fig. 3 is a front or head end view of the tool illustrated in Fig. 1;

Figs. 4, 5 and 6 are detail views of the tool body member or stem;

35 Fig. 7 is a view similar to Fig. 1 but illustrating a modified construction thereof according to which the working head of the tool is interchangeable; and

Fig. 8 is a section taken along line 8—8 of Fig. 7.

40 Referring to the drawings wherein like reference characters designate like parts throughout the several views, a tool according to the modification illustrated in Figs. 1—6 is of rod-like construction and comprises a hollow stem 10 forming the tool body member, the outer surface of which may be provided throughout its major length with knurls or ribs 11 whereby the stem may be firmly gripped with one hand. The head end 12 of the stem is shown to be of reduced external diameter and is formed with outwardly extending ears 13, 14 (Figs. 3 and 6) spaced by a longitudinal slot 15. One end of an outwardly inclined arm 16 is inserted into the slot 15, being securely affixed to the head ears by screws 55 18, 19, the other end of the arm extending for

wardly of the head and terminating in a working point 11.

Journalled for rotation within the bore of the stem 10 is a spindle 20, the head end 20a of which extends beyond the head 12 of the stem and being provided in its extended end with a diametrical slot 21 (Fig. 3). An outwardly inclined arm 22 having an offset inner end is inserted into the slot 21, being secured by set screws 24, and its other end which extends forwardly of the head end 20a and in parallelism with arm 16 terminated in a working point 23. By reference to Figs. 1 and 3, it will be seen that the working points 11, 23 are offset laterally of the axis of stem and spindle to extend parallel to each other and to said axis, and that by reason of the inclination of the arms 16, 22 carrying said points, the latter extend substantially forwardly of the tool body parts.

According to the invention, an irreversible power-developing mechanism for turning the spindle 20 relative to stem 10, thus to effect angular displacement of the working points 17, 23 with the minimum of effort, is provided. To this end, the spindle 20 carries at its rear or driving end a worm gear 26 engaging on one side a spindle shoulder and held against axial shifting on its other side by a retaining ring 27 sprung into a groove 28 cut into the reduced end of the spindle. The worm gear 26 is enclosed within an enlarged housing 30 which may be integrally formed at the driving end of the stem 10 but which is shown to be formed as a separate part which is secured to the stem so as to be angularly adjustable relative thereto. To effect this adjustment, the housing 30 has a hub-like projection 31 terminating in teeth 32 which mate with teeth 33 cut into the end face of the stem 10. An elongated guide and wear bushing 34 fitted into the housing hub 31 extends as shown into an enlarged end bore 35 formed at the driving end of the stem. To secure the hub 31 and its bushing 34 to the stem in desired position of angular adjustment relative thereto, a set screw 36 is threaded into a tapped hole 37 provided in the end of the hollow stem, the set screw having a small diameter tip 38 extending into an annular groove 39 cut into the stem end of bushing 34. Thus, upon the housing being angularly adjusted relative to stem, as permitted by teeth 32, 33, insertion of the set screw 36 assures that the housing and stem are secured against axial separation.

Arranged within the housing 30 and meshing with the worm gear 26 is a worm 40 mounted on a small diameter cross shaft 41 journalled in the side walls of a housing extension 42 (Fig. 2), the cross shaft having one end extending to the exterior of the housing and terminating in a square or hex head 43 whereby the shaft can be turned by a crank lever, wrench or the like. Turning of the shaft as aforesaid, through rotation of worm 40 and gear 26, effects rotation of the spindle 20 within the stem and a corresponding angular displacement of the working points 17, 23. By providing a high gear ratio between worm and worm gear, the latter have a power developing effect permitting turning of the spindle 20 with minimum effort and low friction. Hence, the tool is well adapted for the handling of retaining rings of the larger sizes which require relatively high force to spread or contract. Moreover, a worm gear drive as aforesaid being irreversible assures that the tool is substantially self-

locking in any position to which the working points are spread or contracted.

According to a further feature of the invention, the tool heads and points carried thereby are interchangeable for use with rings of different sizes and of different size of ear apertures. Referring to the modification illustrated in Figs. 7 and 8, the tubular stem 45 forming the body of the tool at its driving end is provided with a gear housing 46 of the form generally shown in the prior modification, the housing enclosing a gearing 49 adapted to be operated by a handle 50 as earlier described. The head end 51 of the body stem 45 is, however, formed as a separate part and is telescoped on to the reduced end 52 of the stem, as shown in Fig. 8. To secure the stem and head against relative rotation, the head is provided with a plurality of axial tongues 53 engaging corresponding recesses or grooves 54 cut into the shoulder in which the reduced end 52 of the stem terminates. Thus, for example, if four such tongue and recesses are provided, the head 51 can be adjusted to any one of four different angular positions relative to the stem 45. To secure the removable head 51 against axial movement relative to the stem, the reduced end 52 of the latter is provided with an annular groove 55 for receiving the end of a screw 56 threaded into a tapped hole 57 of the head.

The stem 45 houses a spindle 48 corresponding generally to the spindle 20 of the prior modification, but differing therefrom in having a removable head end 58. The latter is provided with a collar 59 bearing against an interior shoulder 60 formed in the bore of the removable stem head 51, and also against the edge of the reduced end 52 of the stem, so that upon securement of the stem head 51 the spindle head 58 is also secured in place. As also shown in Fig. 8, the removable spindle head 58 is secured against angular movement relative to spindle 48 proper by a tongue and groove connection 62, 63, as shown.

The removable stem head 51 is provided with ears 65, 66 corresponding to the ears 13, 14 of the prior modification for securing an arm 67 carrying a working point 68 to the head. Similarly, the detachable spindle head 58 is provided with an end slot for fixedly securing the arm 69 carrying the working point 70 for rotation with the spindle. The aforesaid working points correspond to the working points 17, 23 of the earlier described embodiment.

With the above described construction, the interchangeable heads may be removed for the substitution of heads provided with differently sized working points by the simple expedient of freeing screw 56 until its end clears the circular groove 55, whereupon the heads may be axially slipped from the stem 45 and spindle 48, respectively.

It will be observed from the above that both of the illustrated forms of the invention provide a rod-like tool having working points which extend forwardly of the tool proper and are offset from the tool axis, together with means for turning the tool spindle so as to effect angular displacement of the working points and hence either spreading or compressing of a ring with which the points are coupled. Due to its rod-like construction and the offset arrangement of points to body portion, the tool is well adapted for insertion into bore openings of restricted size. Moreover, due to the high ratio worm gearing which serves to couple the stem and spindle of the tool and to effect relative rotation therebetween, a

tool as aforesaid provides a simple means of spreading or compressing even a large ring with one hand while the tool is held in the other, the high gear ratio between worm and worm gear permitting spreading or compressing of the larger size rings with a minimum of effort and with a low friction loss.

As many changes could be made in carrying out the above construction without departing from the scope of the invention, it is intended that all matter contained in the above description or shown in the accompanying drawings shall be interpreted as illustrative and not in a limiting sense.

We claim:

1. A rod-like tool for contracting or expanding retaining rings comprising an elongated tubular handle member, an elongated spindle member coaxially journaled for rotation in the handle member, a projection on each member extending beyond one and the same end of each member, said projections terminating in portions offset from the axis of said members, a work-engaging pin on each of said portions, said pins being parallel to each other and to the axis of said members, and irreversible power-developing mechanism connected to said members for creating relative movement of rotation between them for actuating said work-engaging pins.

2. A rod-like tool as set forth in claim 1, where-
in the projections on the handle and spindle

members comprise outwardly and forwardly inclined arms.

3. A rod-like tool as set forth in claim 1, where-
in the irreversible power-developing mechanism
includes a worm gear on the other end of the
spindle member, and a worm mounted for rotation
in the other end of the tubular handle mem-
ber and having meshing engagement with the
worm gear.
